UNITED STATES PATENT OFFICE.

CLARENCE E. BEACH, OF BINGHAMTON, NEW YORK, ASSIGNOR TO GEORGE O. KNAPP,
OF NEW YORK, N. Y.

SIGNALING SYSTEM AND APPARATUS.

1,101,987.

Specification of Letters Patent. Patented June 30, 1914.

Application filed June 11, 1913. Serial No. 773,063.

To all whom it may concern:

Be it known that I, CLARENCE E. BEACH, of Binghamton, Broome county, State of New York, have invented new and useful 5 Improvements in Signaling Systems and Apparatus, of which the following is a specification.

My invention relates to signaling systems, and concerns particularly the construction 10 and operation of signaling units, whereby units such as fire alarm boxes on street corners, may be caused to be set in operation from remote points.

More particularly the invention involves 15 a simplified arrangement in signaling or alarm boxes, and an improved circuit arrangement whereby auxiliary alarm or signaling circuits can be controlled from remote points to cause the box to be set in 20 operation to send in signals or alarms.

My invention is particularly adaptable to the fire alarm field, where fire alarm boxes are placed at street corners and auxiliary alarm circuits, installed in buildings, are to 25 be connected with such boxes to control the tripping thereof. In prior systems of this class, complicated mechanism has been attached to the fire alarm boxes for taking care of the auxiliary control, such additional 30 apparatus usually involving electro-magnetic mechanism and leverage mechanism connecting with the alarm box parts, and also extraneous setting mechanism. The circuits for such prior systems also require 35 separate current sources and no provision is made so that fire alarm officials or inspectors can ascertain the condition of the auxiliary system by looking at the box. In general, said prior systems are very complicated 40 and not always reliable.

Among the important objects of my invention are to provide such arrangement for accommodating auxiliary remote control circuits that all controlling mechanism for such 45 circuits can be placed within the alarm movement case as an intimate part of the mechanism therein; to provide such arrangement that extra electro-magnetic mechanism and current source for the auxiliary system 50 can be entirely dispensed with; to provide such arrangement that the auxiliary circuit forms merely an adjusting and controlling circuit for the signaling box magnet; to provide an arrangement whereby the current control for the non-interference electro- 55

magnet by the auxiliary circuit is accomplished by a minimum number of simple lever mechanisms applied to the main box mechanism as an intimate part thereof; to provide such arrangement that a mere inspection of the main signaling box from the exterior thereof will indicate the condition of the auxiliary system and whether or not such system is set for operative control of the box; to provide a system of auxiliary 60 control which is not confined for use in connection with one style of signal box but which can be applied to other existing styles of boxes; and in general, to provide a more simplified arrangement in fire alarm boxes 65 which will enable the box to be accurately and efficiently controlled from remote points without the use of expensive and complicated extraneous mechanism, such as has been heretofore resorted to. 70

In the accompanying drawings in which I have illustrated the application and operation of my invention Figure 1 is a front elevational view of a fire alarm box signaling mechanism showing the auxiliary circuit 80 controlling mechanism applied, and in the not set position, Fig. 2 is a top view, Figs. 3 and 4 are sectional views on lines 3 and 4 respectively of Fig. 1 showing auxiliary circuit controlling switch mechanism, Fig. 5 is 85 a front elevational view of the various inclosing casings, Fig. 6 is a horizontal sectional view showing the casing arrangement, and Fig. 7 is an elevation of a detail of the mechanism. 90

In the drawings, the magnet 10 has the armature structure 11 pivoted at 12 and connected at its upper end with a spring 13 which tends to keep the structure in retracted position. The end 14 of the downwardly extending arm 15 in the armature structure co-operates with signal wheel 16 mounted on the shaft 17 of the signaling train designated as a whole by S, this train being driven by spring power, not shown, but 100 which is readily understood in the art. The teeth t of the signal wheel and the notches between the teeth control the operation of the signaling contact 18, which co-operates with another signaling contact 19 to control the signaling circuit. At its periphery the signal wheel carries a lateral flange 20 which is broken in correspondence with the breaks between the teeth and which, at times, serves 105 to lock the armature structure in attracted 110

position and to release the armature structure when its end 14 is opposite the notches between the teeth, this operation being also understood in the art. An L shaped arm 21 is pivoted at 22, and pivoted at an intermediate point to the upper end of this arm is the detent lever 23, whose one end co-operates with the pin 24 on the armature structure and whose other end co-operates with the extension 25 on the escapement pallet 26 associated with the signaling train. The right end of the arm 21 has upper and lower abutment steps 27 and 28 which co-operate with a pin 29 extending from a wheel 30' on shaft 17, a spring 31 engaging with the left end of the arm 21 tending to swing the arm in a counter-clockwise direction. When not set, the parts are in the position as shown in Fig. 1, the pin 29 engaging the sloping left hand side of the abutment on arm 21 near the top step 27 so that the right end of the arm 21 is held down to allow the right end of the detent lever 23 to assume stop engagement with the pallet extention 25 when the armature structure is retracted. The contact block 32 carries two main circuit terminals, 33 and 34. The terminal 33 carries a contact extension 35 and the terminal 34 carries a contact extension 36, and these contact extensions co-operate to open and close a box shunt, as will be described later. The left end of arm 21 carries a contact 37 which is adapted to engage with contact extension 36 to disconnect said contact extension from the contact extension 35 and to close a shunt around the signaling contacts, as will be described later, the arrangement being such that when contacts 37 and 36 are in engagement, the signaling circuit contacts 18 and 19 will be shunted and the box shunt opened, and when contact 37 is moved away from contact 36, both the non-interference magnet and the circuit contacts will be shunted; that is, the main line terminals 33 and 34 will be shunted. Pivoted at its right end is a main locking lever 38 whose left end carries a shunting bar 39 adapted for engagement with the main line contacts 33 and 34 to short-circuit the main line. This locking lever also carries a pawl abutment 40, which, when the lever is down, is in the path of the abutment pin 41 on the large gear wheel 30 of the train. When not set, the main locking lever is down, to effect direct connection through bar 39 between the main line terminals, and the pin 41 abuts against pawl 40 so that the train is locked. A main pull lever 42 is suitably pivoted with its inner end extending below the locking lever 38 so that when the other end of the pull lever is depressed the locking lever will be raised to remove the main line shunt and to allow the train to operate, provided the electro-magnet is energized upon such pulling of the box. A pin 75 is

so located on the locking lever that when the lever is lifted to release the train the step 76 of arm 77 may be drawn by the spring 78 under the pin to hold the lever 38 up so as to keep the main shunt open.

Upon attraction of the armature, the pin 24 will engage the detent lever to swing the right end thereof away from the pallet extension so that the train can operate. After the train begins to operate, and so long as the upper step 27 is associated with pin 29, the detent lever will remain in the field of the pallet, but as soon as pin 29 leaves this upper step, the arm 21 can swing in counter-clockwise direction to carry the lower step 28 into engagement with pin 29 and to raise the detent lever so that it can no longer co-operate with the pallet extension. The co-operation of pin 29 with the upper and lower steps of arm 21 is during the period when the end 14 of the armature structure co-operates with that section of the flange 20 in advance of the first notch of the signal wheel, and substantially at the time the pin 29 leaves the lower step 28 on arm 21, the end 14 of the armature structure will arrive at the first notch, and the arm 21 can then swing further upwardly. Thus, during engagement of pin 29 with the upper step 27, the armature structure controls the pallet mechanism so that attraction of the armature will swing the detent lever away from the pallet mechanism, to allow the train to operate, and retraction of the armature structure will allow spring 23' to restore the detent lever to stop the pallet mechanism and the train; and when pin 29 reaches the lower step 28 of the arm 21, the armature is no longer in control of the running train. The armature structure 11 has also an extension 43 for co-operating with the contact 36. The end 14 of the armature structure is normally above the flange 20, and the armature can be attracted sufficiently to release the train, but not sufficiently to carry extension 43 against contact 36. Pin 29 normally engages with arm 21 to cause contact 37 thereof to engage contact 36 to close the shunt about the signaling contacts 18 and 19, and such shunt is maintained after the box is pulled and during the entire engagement of the pin 29 with the upper step 27 or during the time that the armature has control of the pallet mechanism. Such engagement of the contacts 37 and 36 is also maintained during the time that the pin 29 engages with the lower step 28 and it is not until pin 29 leaves this lower step that the arm 21 can swing sufficiently to break the shunt about the signaling circuit contacts, and when this is effected, the signal circuit contacts will have closed, and thus be ready to break the signal circuit for the first time. At this time also, the end of the armature structure is in association 130

with the first notch of the signal wheel and the armature structure is in full control and can be fully attracted to hold the box shunt contacts 36 and 35 open, or to retract upon 5 opening of the line at other boxes to close the box shunt and thus prevent interference.

Coming now to the improvements and arrangements for allowing control of the box from remote points, auxiliary setting mechanism is provided for actuating the locking lever 38 to unlock the box and to allow operation thereof when the non-interference magnet is energized. The pivot shaft 38' to which the locking lever is secured, has, 15 at its outer end, a crank arm 44 secured thereto, and provided with a crank pin 44'. On a shaft 45, extending forwardly from the box mechanism supporting frame, is pivoted a hub 46 to which is secured a 20 substantially vertically extending lever 47 whose upper end is adapted to act against crank pin 44' to effect swing of the crank arm and of the locking lever 38. Extending horizontally and toward the left from 25 the hub and having preferably detachable connection therewith, is a setting arm 49, which, when raised, will turn the hub 46 and swing the upper end of the lever 47 to thereby effect raising of the locking lever 38. A 30 spring 50 connected between the upper end of the lever 47 and any stationary frame part tends to resist the setting movement of the setting mechanism and to restore the setting mechanism to normal position when 35 released. Pivoted at an intermediate point adjacent to the setting mechanism, is a detent lever 51 whose left end 51' is overbalanced or provided with spring control which will cause the end 51'' to engage in front of 40 pin 48 extending from the upper end of lever 47 after the setting arm 49 has been raised, so as to lock the setting arm and lever 47 in set position against the power of the spring 50. It should be noted that the 45 pin 75 should lock the arm 38 on step 76 simultaneously with or not later than the locking of pin 48 by detent lever 51. A tongue 52 on lever 51 extends downwardly into the path of the inner end of the main 50 pull lever 42, so that when the box is pulled in the ordinary manner, the detent 51 will be swung to release the pin 48 to allow the setting mechanism to return to unset position. The inner end 51' of this detent lever 55 also projects into the path of pin 53 on the signal wheel 16 of the box train, this pin being so situated that at the beginning of a round of the signal wheel the detent lever will be swung to trip the auxiliary setting 60 mechanism, the purpose of such tripping being described later.

The lower end of lever 47 carries a block 54 of insulating material, through which extend upper and lower switch bars 55 and 65 56. Adjacent the lower end of lever 47 is

a block 57 of insulating material mounting upper contact springs 58 and 59 and lower contact springs 60 and 61. The upper contact springs are sufficiently long to engage with the opposite ends of switch bar 55 when 70 the auxiliary setting mechanism is unset, and to become disconnected from the bar when the auxiliary mechanism is set. The lower contact springs are shorter so as to be away from the lower switch bar 56 when 75 the auxiliary mechanism is unset and to come into electrical engagement with the opposite ends of the bar when the mechanism is set.

The main line conductors L, L', connect 80 respectively with the contacts 33 and 34 so that when the locking lever 38 is down, its contact bar 39 will short-circuit the main line and bridge out all the box mechanism. The main contact 34 connects through conductor 63 with signaling contact 19 and the signaling contact 18 connects through conductor 64 with one terminal of the winding of the non-interference electro-magnet 10, the other terminal of this winding connecting 90 through conductor 65 with the main contact 33. Contact 37 on arm 21 connects through conductor 66 with contact 18. One limb *a* of the auxiliary circuit A connects with spring 60 of the auxiliary mechanism, spring 95 61 of this mechanism connecting through conductor 67 with the main terminal 33. This spring 61 also connects through conductor 68 with spring 58, and spring 59 connects through conductor 69 with that terminal of 100 the electro-magnet winding which is connected to main contact 33. The other limb *a'* of the auxiliary circuit A connects with main contact 34. The limbs *a* and *a'* are, of course, normally connected together 105 through any number of switch devices *s* which enable this circuit to be opened at various points. If the auxiliary circuit A is to be connected for service, the setting arm 49 is raised to a set position and is then 110 locked in set position by the pin 48 and detent lever 51. When thus set, the box is ready for operation as soon as the electro-magnet can become energized. This electro-magnet is connected serially with the main 115 line as follows: from main contact 33 to conductor 65, electro-magnet winding, conductor 66, contact 37, contact 36 and main contact 34. However, when setting has been accomplished, the auxiliary line A will offer 120 a short circuit path around the electro-magnet winding so that even though the box has been unlocked, it cannot operate, as the electro-magnet cannot receive sufficient current flow to control the train locking detent 23. 125 This short circuit is as follows: from the main contact 33 to conductor 67, spring 61, switch bar 56, spring 60, through limbs *a* and *a'* of the auxiliary circuit and to the main contact 34. Substantially the entire 130

main line current will, therefore, flow through the auxiliary circuit and the electro-magnet remains deenergized. If the main electro-magnet winding is of low resistance, it will be advisable to include a resistance R in series with the winding. This resistance is shown in the conductor 65, and forces practically all the current to flow through the short circuit A. The mechanical relation of main shunt 33-39-34 and auxiliary shunt A is preferably such that the operation of setting will close the auxiliary shunt at 60-56-61 before the main shunt is broken at 33-39-34 to avoid energizing the electro-magnet 10. If, now, an alarm is to be sent in from any station on the auxiliary circuit, one of the switch mechanisms s is actuated to open the short circuit, and upon such opening the electro-magnet 10 immediately receives sufficient current flow to attract its armature and the signaling train is released and the box will send in the alarm, provided, of course, that the line is in proper condition to receive the signals. Immediately upon starting of the box, the pin 53 on the signal wheel will engage the detent lever 51 to trip the setting mechanism as before described, and the lower end of lever 47 will swing outwardly to connect contact springs 58 and 59 through bar 55 and to disconnect bar 56 from the contact springs 60 and 61. The auxiliary circuit is then positively opened by the disengagement of the springs 60 and 61, but engagement of springs 58 and 59 through bar 55 will close a short circuit around the resistance R , and this short circuit includes conductor 69, spring 59, bar 55, spring 58, conductor 68 and conductor 67. The non-interference electro-magnet is thus restored to its normal condition to control the running of the box and to prevent interference. After such signaling operation of the box and after the auxiliary circuit has been closed outside of the box, the setting mechanism is again restored to set position and the auxiliary circuit is then finally closed in the box by the bar 56 and contacts 60 and 61.

It is very important that the setting mechanism be tripped to positively open the auxiliary circuit at contacts 60 and 61 before the box signaling contacts become effective to send in signals, as otherwise the auxiliary circuit could be accidentally closed at remote points and the non-interference electro-magnet rendered inoperative and its armature structure released to shunt out the box during a signal. The pin 53 on the signaling mechanism is therefore so set with reference to the tripping lever 51 that the setting mechanism will be tripped and the auxiliary circuit positively opened and kept open at contacts 60 and 61 within the box before the signaling contacts become effective. The as-

sociation of the above described setting or circuit controlling mechanism for the auxiliary circuit will not interfere with the normal pulling and operation of the box, for as soon as pull lever 42 of the box is actuated, the tripping lever 51 is simultaneously moved to trip the setting mechanism so that the auxiliary circuit is positively opened when the box starts and is kept open during the entire operation of the box, independently of the condition of the auxiliary circuit. Of course, after a box has been operated either directly or by means of the auxiliary circuit, the setting mechanism will have to be re-set to restore control of the box to the auxiliary circuit.

In order to determine whether or not a box is set for auxiliary circuit control, provision is made so that the setting mechanism or part thereof is visible from the exterior of the housing containing the box mechanism. The box mechanism, including the auxiliary circuit controlling parts, is installed in an inner case i and this case is installed within a middle box m which is locked to the public, and this middle box is inclosed in an outer box o which is secured to a pole or other support. As shown in Figs. 5 and 6, the door of the middle box has a hole 70 through which the pull lever 42 projects a sufficient distance to be pulled when the door of the outer box is open. The door of the middle box has also a sight opening 71, through which part of the setting mechanism is visible. As shown, the end of setting arm 49 carries a target 72 having legends thereon, and visible through the sight opening 71 to indicate the condition of the setting mechanism. As shown, the legend "Not set" appears at the top of the target, and the legend "Aux. set" appears at the lower part of the target, the upper legend appearing in front of the sight opening 71 when the mechanism is not set for auxiliary control and the lower legend appearing in front of the sight opening 71 when the mechanism is set for auxiliary control. Preferably, the sight opening is covered at the rear by a glass plate 73 so as to prevent tampering with the setting mechanism. Thus, the position of the setting arm and, therefore, the condition of the auxiliary circuit can be readily determined without opening the middle box, and the box mechanism can be locked against tampering by unauthorized persons. Instead of having words on the target, the upper part thereof may be of one color and the lower part of another color, to indicate the condition of the auxiliary system, and a sight opening 74 could also be provided in the cover of the outer box so that inspection of all boxes in a line could be quickly made and the condition of the auxiliary circuits quickly determined without the necessity of opening any doors.

It is apparent that, by means of my invention, an ordinary fire alarm box can, by the addition of a few simple elements, be adapted for auxiliary control from remote stations, and all this can be accomplished without the addition of electro-magnetic mechanisms or complicated circuit controlling mechanisms and without the need of special current sources for the auxiliary circuit, the auxiliary circuit in my improved system being merely in the nature of a shunt or short circuit path around the winding of the non-interference magnet of the box. This auxiliary controlling circuit therefore is under constant test for its continuity while the box is set, and can be readily tested from the central station for grounds, etc. As soon as starting of the box has been effected by the operation of the auxiliary circuit, this circuit is positively and automatically disconnected by the box itself, so that the box may carry out its normal operations of sending in its signal. Also, when the box is directly pulled, the auxiliary circuit or circuits emanating therefrom are automatically and positively disconnected so as not to interfere with the normal operation of the box. Furthermore, the condition of the setting mechanism and hence of the auxiliary circuit is visible and readily determined without the necessity of opening the various inclosing doors.

As above stated, my invention can be applied to many kinds of boxes now in use, and any modifications in the construction and arrangement of the setting mechanism within said box would come within the broad scope of my invention. Furthermore, changes and modifications can be made in the particular setting and controlling mechanism shown without departing from the scope of the invention.

I therefore claim the following:

1. In a signaling system, the combination of a signaling train, an electro-magnet for controlling the running of said train, an auxiliary controlling circuit for normally shunting said electro-magnet, setting mechanism adapted when in one position to oper- atively connect said auxiliary circuit with the electro-magnet and adapted when in a second position to disconnect said auxiliary circuit, and means operated by the train for moving said setting mechanism to prevent closing of the auxiliary circuit during the running of the train.
2. In a signaling system, the combination of a signaling train including a signal wheel, signaling contacts associated with said signal wheel, a non-interference electro-magnet for controlling the running of said train, an auxiliary controlling circuit extending from said electro-magnet, setting mechanism adapted when in one position to connect said auxiliary circuit with the non-interfer-
3. In a signaling system, the combination of signal controlling mechanism comprising a signal train and an electro-magnet for controlling the running of said train, main line conductors leading to said signal mechanism, a circuit connecting said electro-magnet with said main line conductors, an auxiliary controlling circuit extending from said signal mechanism, setting mechanism adapted when set to cause connection of said auxiliary circuit with the electro-magnet circuit to short-circuit said electro-magnet circuit to thereby prevent release of the signaling mechanism by the electro-magnet until opening of the auxiliary circuit, switch mechanisms for the auxiliary circuit for controlling the opening thereof, and means operated by the train for moving said setting mechanism to prevent closing of the auxiliary circuit during the running of the train.
4. In a signaling system, the combination of signaling mechanism comprising a signaling train and an electro-magnet for controlling the running of said train, a main circuit extending to said signal mechanism, a circuit for connecting said electro-magnet with said main circuit, an auxiliary controlling circuit extending from said signal mechanism, a resistance in the electro-magnet circuit, and setting mechanism adapted when in set position to close the auxiliary circuit in shunt to the electro-magnet circuit whereby said electro-magnet is controlled to prevent the running of the train, and said setting mechanism when in unset position causing opening of the auxiliary circuit and closure of a shunt circuit about said resistance.
5. In a signaling system, the combination of signaling mechanism comprising a signaling train and an electro-magnet for controlling the running of said train, a main line leading to said signal mechanism, a circuit connecting said electro-magnet with said main line, a main shunt for short-circuiting the electro-magnet circuit, an auxiliary controlling circuit in the form of a shunt about the electro-magnet circuit, and setting mechanism, said setting mechanism when in set position causing opening of the main shunt and closure of the auxiliary controlling circuit whereby said electro-magnet and thereby the running of the train is under the control of the auxiliary circuit.
6. In a signaling system, the combination of signaling mechanism comprising a signaling train and an electro-magnet for con-

70

ence electro-magnet to cause short-circuiting thereof and adapted when in a second position to open said auxiliary controlling circuit, and means operated by the train for moving said setting mechanism to prevent closing of the auxiliary circuit during the running of the train.

trolling the running of said train, a main line leading to said signaling mechanism, a circuit connecting said electro-magnet with said main line, a main shunt for short-circuiting the electro-magnet circuit, an auxiliary controlling circuit in the form of a shunt about the electro-magnet circuit, and setting mechanism, said setting mechanism when moved to set position causing opening 5 of the main shunt and closure of the auxiliary controlling circuit whereby said electro-magnet and thereby the running of the train is under the control of the auxiliary circuit, and means for locking said main shunt in 10 open position after opening thereof by the setting mechanism.

7. In a signaling system, the combination of signaling mechanism comprising a signaling train and an electro-magnet for controlling the running of said train, a main line 20 leading to said signaling mechanism, a circuit connecting said electro-magnet with said main line, main shunt switch mechanism for short-circuiting said electro-magnet circuit, an auxiliary controlling circuit extending from said signaling mechanism, setting mechanism adapted when set to close said auxiliary circuit in bridge of said electro-magnet circuit and adapted 25 when set to open the main switch mechanism whereby said electro-magnet and thereby the running of the train is then under control of the auxiliary circuit, and a pull lever for the signaling mechanism 30 adapted when pulled to cause un-setting of said setting mechanism and thereby opening of the auxiliary circuit to allow the electro-magnet to start the signaling train.

8. In a signaling system, the combination 40 of signaling mechanism comprising a signaling train and an electro-magnet for controlling the running of said train, a main line extending from said signaling mechanism to the central station, a circuit for connecting said electro-magnet with the main line, an auxiliary controlling circuit extending from said signaling mechanism, setting mechanism associated with the signaling mechanism and adapted when set to close 45 the auxiliary circuit in bridge of the electro-magnet winding, a pull lever mechanically associated with the signaling train, and means whereby pulling of said pull lever will cause un-setting of the setting mechanism and opening of the auxiliary circuit to allow the electro-magnet to electro-mechanically release the train.

9. In a signaling system, the combination 50 of signaling mechanism comprising a signaling train and an electro-magnet for electro-mechanically controlling the running of said train, a main line extending from said signaling mechanism to the central station, a circuit connecting said electro-magnet with 55 the main line, main shunt switch mechanism

for shunting said electro-magnet circuit, pull mechanism adapted normally to mechanically lock the train and to close the main shunt switch, an auxiliary controlling circuit extending from said signaling mechanism, setting mechanism adapted when set to close said auxiliary controlling circuit in bridge of the electro-magnet circuit and open said main shunt switch, and means whereby pulling of the pull mechanism will 70 open said auxiliary circuit whereupon said electro-magnet is free to receive sufficient current flow from the main line to electro-mechanically release the signaling train. 75

10. In a signaling system, the combination 80 of signaling mechanism comprising a signaling train and an electro-magnet for controlling the running of the train, a main line extending from said signaling mechanism to a central station, a circuit connecting said electro-magnet with the main line, an auxiliary controlling circuit extending from said signaling mechanism to remote points and connected in bridge of the electro-magnet circuit, normally closed switch mechanism for said auxiliary circuit for controlling the opening thereof at remote points, main switch mechanism for said auxiliary circuit associated with said signaling mechanism, setting mechanism adapted when set 85 to actuate said main switch mechanism to close said auxiliary circuit whereby said electro-magnet will be prevented from starting said signaling train, said electro-magnet becoming effective to start the train upon 90 opening of the auxiliary circuit by any of the remote switch mechanisms, and means controlled by the train in running for causing un-setting of the setting mechanism and re-opening of the auxiliary circuit by said 95 main switch mechanism.

11. In a signaling system, the combination 100 of signaling mechanism comprising a signaling train and an electro-magnet for controlling the running of said train, a main line extending to said signaling mechanism for supplying current flow, a circuit connecting said electro-magnet with said main line, an auxiliary controlling circuit extending from said signaling mechanism to remote 110 points and being in the nature of a normally closed short-circuit about said electro-magnet to prevent operation of said electro-magnet to start the train, switch mechanisms for said auxiliary circuit for controlling the opening thereof to allow operation of the electro-magnet to start the train, and means controlled by the running of the train for permanently opening said auxiliary circuit after primary opening thereof by the auxiliary 115 circuit switch mechanism.

12. In a signaling system, the combination 120 of signaling mechanism comprising a signaling train and an electro-magnet for controlling the running of the train, a main cir- 130

- cuit extending to the signaling mechanism to supply current flow, a circuit for connecting the electro-magnet with said main circuit, a locking lever for the train, an auxiliary controlling circuit, setting mechanism for controlling the connection of said auxiliary circuit with the signaling mechanism, said setting mechanism when moved to set position causing movement of the locking lever to release the signaling train and causing connection of the auxiliary circuit with the signaling mechanism to prevent release of the train thereof by the electro-magnet, and means for controlling the auxiliary circuit from remote points to allow releasing operation of the electro-magnet. 5
- 10 13. In an auxiliarized fire alarm box, the combination of a signaling train, a locking lever for mechanically locking said train, an electro-magnet structure for electro-mechanically controlling the running of the train, a setting lever for controlling the connection of an auxiliary circuit with the signaling mechanism, and means whereby actuation of said setting lever will move the locking lever to release the signaling train and will cause the electro-magnet structure to hold the train. 20
14. In an auxiliarized fire alarm box, the combination of a signaling train, a locking lever for mechanically locking said train, an electro-magnet structure for electro-mechanically controlling the running of the train, a setting lever for controlling the connection of an auxiliary circuit with the signaling mechanism, means whereby actuation of said setting lever will move the locking lever to release the signaling train and will cause the electro-magnet structure to hold the train, and a pull lever for the box adapted when pulled to cause unsetting of the setting lever. 30
15. In an auxiliarized fire alarm box, the combination of a signaling train, an electro-magnet for controlling the running of said train, a setting lever for controlling the connection of an auxiliary circuit with the signaling mechanism and adapted when set to give the auxiliary circuit control of the electro-magnet, and means controlled by the train in running for causing unsetting of the setting lever after said train has been started by means of the auxiliary circuit. 40
16. In a signaling system, an auxiliarized signal box comprising a train including a signal wheel and contacts associated with said wheel, a locking lever for mechanically locking said train, a non-interference electromagnet for controlling the running of said train, a main circuit including a source of current and a translating device, a circuit connecting said electromagnet with said main circuit, main shunt switch mechanism for shunting said electro-magnet circuit, an auxiliary controlling circuit for normally shunting said electro-magnet circuit, normally closed switch mechanisms for said auxiliary circuit, said electro-magnet becoming effective to start the train upon opening of the auxiliary circuit by any of the switch mechanisms, setting mechanism adapted when in one position to operatively connect said auxiliary circuit with the electro-magnet to cause shunting thereof and to open the main shunt and adapted when in another position to disconnect said auxiliary circuit, a setting lever for controlling the setting mechanism, a visual indicator for said setting mechanism, means whereby actuation of said setting lever will transfer the control of the train from the locking lever to the electro-magnet, means controlled by the train in running for causing unsetting of the setting mechanism, means for locking said main shunt in open position after opening thereof by the setting mechanism and a pull lever mechanically associated with the signaling train and adapted when pulled to cause unsetting of said setting mechanism and thereby opening of the auxiliary circuit to allow the electro-magnet to start the signaling train. 50
17. In an auxiliarized fire alarm box, the combination of a signaling train, an electro-magnet for controlling the running of said train, setting mechanism for controlling the connection of an auxiliary circuit with the signaling mechanism and adapted when set to give the auxiliary circuit control of the electromagnet, means for visually indicating the position of said setting mechanism, and means controlled by the train in running for moving said setting mechanism to prevent closing of the auxiliary circuit during the running of the train. 60
18. In an auxiliarized fire alarm box, the combination of a signaling train, means for mechanically locking said train, an electro-magnet structure for electro-mechanically controlling the running of said train, setting mechanism for controlling the connection of an auxiliary circuit with the signaling mechanism, means for visually indicating the position of said setting mechanism, and means whereby actuation of said setting mechanism in one direction will mechanically move the locking means to place the train under the control of the electro-magnet structure. 70
19. In an auxiliarized fire alarm box, the combination of a signaling train, means for mechanically locking said train, an electro-magnet structure for electro-mechanically controlling the running of the train, setting mechanism for controlling the connection of an auxiliary circuit with the signaling mechanism, means for visually indicating the position of said setting mechanism, means whereby actuation of said setting mechanism, 80

- mechanism will move the locking means to release the train and will allow the electromagnet structure to hold the train, and a pull lever for the box adapted when operated to cause upsetting of the setting mechanism.
20. In a signaling system, the combination of signaling mechanism comprising a signaling train and an electromagnet for controlling the running of said train, a main line leading to said signaling mechanism, a circuit connecting said electromagnet with said main line, a main shunt for shortcircuiting the electromagnet circuit, an auxiliary controlling circuit in the form of a shunt about the electromagnet circuit, setting mechanism and a visual indicator therefor, said setting mechanism when in set position causing opening of the main shunt and closure of the auxiliary controlling circuit.
21. In a signaling system, the combination of signaling mechanism comprising a signaling train and an electromagnet for controlling the running of said train, a main circuit extending to said signaling mechanism, a circuit for connecting said electromagnet with said main circuit, an auxiliary controlling circuit extending from said signaling mechanism, a resistance in the electromagnet circuit, and setting mechanism with a visual indicator therefor, said setting mechanism being adapted when in set position to close the auxiliary circuit in shunt to the electromagnet circuit, and when in upset position causing opening of the auxiliary circuit and closure of a short-circuit about said resistance.
22. In an auxiliarized fire alarm box, the combination of a signaling train, an electromagnet for controlling the running of said train, switch mechanism controlling the connection of an auxiliary circuit with the signaling mechanism, an indicating operating lever for said switch mechanism, a latch for said switch mechanism, and means operated by the train in running for releasing said latch.
23. In an auxiliarized fire alarm box, the combination of a signaling train, an electromagnet for controlling the running of said train, switch mechanism controlling the connection of an auxiliary circuit with the signaling mechanism, an indicating operating lever for said switch mechanism, a latch for said switch mechanism, a pull lever for said train, and means operated by said pull lever for releasing said latch.
24. In an auxiliarized fire alarm box, the combination of a signaling train, an electromagnet for controlling the running of said train, a spring switch for controlling the connection of an auxiliary circuit with the signaling mechanism, an indicating operating lever for said switch, a holding latch for said switch, and means operated by the train in running for releasing said latch.
25. In an auxiliarized fire alarm box, the combination of a signaling train, an electromagnet for controlling the running of said train, a spring switch for controlling the connection of an auxiliary circuit with the signaling mechanism, an indicating operating lever for said switch, a holding latch for said switch, a pull lever for said train, and means operated by said pull lever for releasing said latch.
26. In an auxiliarized fire alarm box, the combination of a signaling train, means for mechanically locking said train, an electromagnet structure for electro-mechanically controlling the running of the train, switch mechanism controlling the connection of an auxiliary circuit with the signaling mechanism, an indicating operating lever for said switch mechanism, means whereby actuation of said switch mechanism will move the locking means to release the train and will allow the electromagnet structure to hold the train, a holding latch for said switch mechanism, and a pull lever for the box adapted when operated to release the holding latch.
27. In a signaling system, the combination of signaling mechanism comprising a signaling train and an electromagnet for controlling the running of said train, a main line leading to said signaling mechanism, a circuit connecting said electromagnet with said main line, a main shunt for shortcircuiting the electromagnet circuit, an auxiliary controlling circuit in the form of a shunt about the electromagnet circuit, indicating switch mechanism and a latch therefor, said switch mechanism when latched causing opening of the main shunt and closure of the auxiliary controlling circuit.

In witness whereof, I hereunto subscribe my name, this seventh day of June, A. D. 1913.

CLARENCE E. BEACH.
